RECESSING CUTTER

William Barnes Crockett, Notre Dame de Grace,
Quebec, Canada

Application September 13, 1933, Serial No. 689,334

9 Claims. (Cl. 29—69)

This invention relates to recessing cutters and an object of the invention is to provide a compact tool of this character which may be inserted within tubes or the like to cut into the interior surface of the tube.

A further object of the invention is to provide a device of this character including simple means for locating the cutter within the tube and means for gauging the extent of the cut.

10 A further object of the invention is to provide a tool made up of parts arranged in a simple and compact manner having a shaft driven from a compact power unit.

With these and other objects in view, the invention consists essentially of the novel construction and arrangement of parts described in the following specification and illustrated in the accompanying drawings.

In the drawings:

20 Figure 1 is a side elevation of a tool in complete assembly showing the cutter end and the opposed or driving end partly in section.

Figure 2 is a longitudinal sectional elevation of the tool without the power unit, showing it mounted in position to be introduced within a tube.

Figure 3 is an enlarged fragmentary elevation of the rear end of the tool which connects with the power unit illustrating the gauge sleeve.

30 Figure 4 is an end elevation of Figure 3.

Figure 5 is an end elevation of the plurality of sleeves forming the tool but without the cutter operating shaft and cutter.

35 Figures 6 and 7 are detail elevations of the clip construction for retaining the locating member.

Figure 8 is a fragmentary illustration of the end of the cutting tool illustrating the mounting of the shaft by means of eccentric sleeves, the sleeves being shown in their normal position.

40 Figure 9 is an end elevation of Figure 8.

Figure 10 is an end elevation of Figure 8 with the cutter removed showing the relative position of the shaft and the eccentric sleeve and casing.

45 Figure 11 is a similar view to Figure 8 showing the sleeves in eccentric position to throw the cutter out beyond the edge of the tool.

Figure 12 is an end elevation of Figure 11 showing the cutter disposed eccentrically to the casing, and

50 Figure 13 is an end elevation of Figure 11 with the cutter removed to show the position of the eccentric sleeves and casing when the sleeves have been operated to project the cutter eccentrically of the casing.

55 Referring more particularly to the drawings,

A indicates the tool as a whole and B indicates the power unit therefor. The tool consists of a central shaft 10 designed to carry the recessing cutter blade or blades 11 on one end and to connect as at 12 (see Figure 2) by means of a pin with a socket 13 of the drive shaft 14, the drive shaft being formed with a shank 15 engageable with the rotating element of the power unit. The shaft 10 is mounted within a long sleeve bush 16 which is bored eccentrically of its center to carry said shaft (see Figures 2, 8 and 9 particularly). The sleeve bush may be formed concentric to the power end and eccentric at its opposite end.

As noted in Figure 2, the member 16 is provided with an enlarged end 17 which is bored to house the drive shaft 14, the enlarged end thereof forming a shoulder 18 for the reduced portion of the sleeve bush. A second sleeve bush 19 which forms the outer casing of the tool is designed to house the sleeve 16, the sleeve 19 or outer casing being bored eccentrically of its center and when the two sleeves are mounted in position the eccentric portions thereof are disposed opposite to one another as shown in Figure 8 so that the shaft 10 is centrally located and the axis of the cutter blade is concentric with the outer sleeve bush.

In structure the outer sleeve bush or casing 19 is formed with an enlarged end 20 having an enlarged bore designed to house the enlarged end of bush 16 and the shoulder 18 of this latter bush will abut a corresponding shoulder on the enlarged end of the sleeve member 19 so that when the latter is secured in mounted position on the power unit the sleeve 16 and shaft 10 will be held firmly.

The enlarged end 20 of member 19 is provided with a slot 21 which extends half-way around the circumference of this end and through this slot an operating lever 22 is projected and rigidly engaged by screw threading or the like 23 with the enlarged end 17 of sleeve bush 16. Consequently, upon giving the lever 22 a rotary movement, the sleeve 16 can be rotated with respect to the sleeve 19 so that the eccentric portion of the sleeve bush 16 is moved from its normal position to dispose the bore of this sleeve bush eccentric to the outer surface of sleeve bush 19, as disclosed in Figure 9. Thus, the cutter blade is projected beyond the surface of the sleeve 19 and if it is inserted within a tube the cutter will engage with the walls thereof so that on rotation of the shaft a recess will be cut in the tube.

On the end of the enlarged head 20 of sleeve bush or casing 19 a collar 24 is mounted. This collar is formed with a slot 25 (see Figure 3) through which projects a pin 26 rigidly mounted in the enlarged end of the casing and a thumb screw member 27 is threaded on pin 26 so that its lower surface can be brought into engagement with the sleeve to hold it in a desired position. The slot and pin also serve to hold the collar from axial movement. A recessed portion 28 is provided in the collar member which registers with the slot 21, the recess extending over one-half the circumference of the collar so that it can be moved to register exactly with the slot 21. This will permit the lever 22 to be moved 180° in the slot and thus move the recessing cutter blade to an extreme position projected beyond the surface of the casing 19 or to a position in which the teeth of the cutter are flush with the surface of the casing, as shown in Figure 8.

It will be further noted that the collar member 24 is provided with a series of graduations and the large end of the casing is provided with a projecting pin 29 with which these graduations may be aligned so that by rotating the collar to align any given graduation with the pin the recessed portion may be caused to move out of full registry with the slot 21 and thus limit the extent to which the lever may be moved in this slot. For instance, as shown in Figure 3, the lever can only be moved one-half its normal amount because the collar has been moved to register its lowest graduation with the pin. If, however, the collar is rotated so as to cause the graduation 10 to register with pin 29 the recess will be brought into complete registry with the slot 21 to permit maximum movement of the lever. In this way, the collar and slot arrangement provides means for gauging the depth of a recess to be cut since the operator may, by setting the collar, move the cutter eccentrically of the casing to a desired extent.

Mounted on the casing or sleeve bush 19 is a sleeve 30 which may be termed a locating member. This sleeve is designed for axial movement on the casing 19 and terminates adjacent to one end thereof. The sleeve is of a diameter considerably greater than the casing 19 so that when the casing is inserted within the tube the end of the sleeve or locating member 30 may abut the end of the tube to stop further movement of the casing into the tube. On the opposite end of the sleeve is mounted a spring clip 31 which carries a pin 32 having a knurled operating piece 33. This pin is designed to project through an orifice in the sleeve 30, as shown in Figure 2, and between the clip and the sleeve is provided a cam member 34 which is formed with a curved lower surface to snugly fit against the side of the sleeve. The cam member is rigidly secured to the pin 32 so that it will rotate therewith and if it is given a turn of 90° the curved lower surface which forms a cam member during turning of the pin will be moved out of engagement with the sleeve so that the ends 35 of the cam member (see Figure 7) will be moved to a position in alignment with the longitudinal axis of the sleeve and form the only point of contact between the cam member and the sleeve so that the pin will be raised until its end is flush with the inner surface of the sleeve.

As noted in Figure 2, a series of circular recesses 36 are provided in the casing 19 in alignment with one another, the recesses being of a size to receive the pin 32. These recesses are dis-

posed at definitely spaced intervals from one another (see Figure 3).

On the side of the sleeve 19 and positioned at 90° from the recesses 36 are provided a plurality of recesses or markings 31, these markings being placed in a definite relation to the recesses 36. Cooperating with these markings is a recessed portion 38 on the end of sleeve 30 so that when the sleeve 30 is moved on the casing 19 to bring the recess 38 so that it registers with a given markings 31, as shown for instance in Figure 1, the pin 32 is in a position registering with a recess 36 corresponding to the marking 37. In this way the recesses 36 may be located to permit insertion of the pin 32 therein and it is only necessary to rotate the pin one quarter turn to cause the curved surface of the cam member 35 to again lie flush with the outer surface of the sleeve, thus lowering the pin into the recess 36. Consequently, the recess in the end 20 of the sleeve and the markings or recesses 31 constitute means for locating the pin and the recesses 36, the recesses 36 locating the cutter blade in the tube since they position the sleeve 30 axially on the casing 19 so that the ends of this casing and the cutter project from the sleeve 30 to a greater or lesser extent.

In order to provide a guide and steadyng member for the tool, a bracket or the like 39 is secured to the outer sleeve 30 and is provided with a channel 40 to receive the guide rod 41 which may be projected into an adjacent tube to that being recessed, and thus it will serve as a guide and steadyng member for the tool when operating upon an adjacent tube. The outer casing and assembled parts of the tool are attached to the motor by means of a collar member 42 which is provided with a knurled surface for gripping purposes. The collar is secured by means of a threaded bushing or the like 43 which is provided with a flanged head as shown to abut a shoulder cut on the inside of the collar 42. Between the outer surface of this bushing and the collar in a recess formed in the latter, a lock spring 44 is positioned in this recess and permits smooth rotational movement in a clockwise direction to screw the collar onto the screw threaded end 45 of the casing, but provides substantial resistance to rotation in an anti-clockwise direction, thereby avoiding the possibility of this becoming loosened through vibration. When the motor is fitted to the collar, the socket 46 in the driving spindle will engage the end 15 of the shaft 10 so that upon setting the motor in motion the shaft and carried cutter 55 will be rotated.

In one of its applications the device may be used for instance to remove copper tube beads, such as shown at 47 (Fig. 2) from the grooves of feed water heated tube sheet holes when removing old copper tube for renewal purposes. Among other uses it may be applied to internally cut out tubes that have been expanded from the inside bore in such a manner that the outer wall of said tube is stretched or pressed into grooves 65 in solid walls. In fact its application is wide in the field of recessing and cutting.

In operation, assuming that it is desired to cut out the beads 47 in the tube as shown in Figure 2, the cutter being in the position illustrated in Figure 1 or 2 which is concentric with the outer casing 19, is inserted into the tube the distance the beads are formed from the end of the tube. The locating member or sleeve 30 may be first adjusted through the pin 32 and the recesses 36 so

that when the outer end of the casing is inserted in the tube, the cutter will be positioned in its proper place through the abutment of the end of the locating member 30 with the tube sheet wall.

- 5 According to the depth of the bead, the gauge collar 24 may be set so that its recess may be moved relatively to the slot 21 so that the collar will restrict the length of the slot 21 in the enlarged portion 20 of the casing 19 so that the lever 22 may be moved the appropriate distance to rotate the sleeve bush 16, whereby the cutter is projected eccentrically to the required extent. The gauge for setting the degree of eccentricity of the cutter as noted reads from 5 to 10 representing .050 inch to .0100 inch so that the cutter may be moved with accuracy to a very minute degree.

When adjustment has been made, the motor is set in operation and the cutter, rotated through 20 the shaft 10, will cut the required recesses, whereupon the severed parts may be removed in a practical known manner.

It is apparent from the foregoing that the tool I have produced is very simple and practical 25 and that it will provide for accuracy in operation, being compact in form and readily manipulated.

Various modifications may be made in this invention without departing from the spirit thereof or the scope of the claims, and therefore the 30 exact forms shown are to be taken as illustrative only and not in a limiting sense, and it is desired that only such limitations shall be placed thereon as are disclosed in the prior art or are set forth in the accompanying claims.

35 What I claim is:—

1. A recessing cutter comprising a shaft, a cutter mounted on the shaft, said shaft being mounted in a sleeve bush having an eccentrically cut shaft receiving bore, an outer casing for said 40 sleeve bush having an eccentrically cut bore for receiving said bush, the bore of the sleeve bush and bore of the casing being normally disposed eccentric to one another whereby said shaft is concentric with the outer surface of the casing, a slot in the outer casing, a lever member projecting 45 through said slot and mounted in the sleeve bush whereby on movement of the lever in one direction said sleeve bush is rotated to project the cutter eccentrically of the casing, means mounted on 50 said casing co-operating with the lever and slot for gauging the rotational movement of said sleeve bush, a power unit for operating the cutter and means for uniting the power unit to the casing in operative connection with the shaft.

- 55 2. The device as claimed in claim 1 in which means is provided on the casing for gauging the depth to which the cutter is projected in a tube or opening.

3. The device as claimed in claim 1 in which 60 the means co-operating with the lever and slot comprises a collar mounted on said casing, said collar having a recess corresponding in size and designed to register with said slot to provide for maximum adjustment of the lever, said collar being rotatable to vary the degree of registration between the slot and recess, and means for 65 securing the collar in adjusted position.

4. The device as claimed in claim 1 in which the power unit is secured to the casing by means of a rotatable screw threaded collar and wherein means are provided for resisting rotational movement of the collar in one direction.

5. In a recessing cutter including a casing carrying a rotatable cutter and means for moving said cutter into cutting position, means mounted on the casing for locating the cutter at a given point within a tube including a 10 slideable sleeve, a spring clip mounted on said sleeve, a pin carried by the clip designed to project through an orifice in the sleeve, said clip normally urging said pin towards the casing, the latter having a plurality of spaced apart aligned recesses, the said 15 pin being projected and locked in said recesses by the clip when in registry with the recesses and cam means associated with the pin operative to hold said pin out of said recesses.

6. The device as claimed in claim 5 in which 20 means is provided for locating said pin in registry with said recesses.

7. In a recessing cutter including a casing, carrying a rotatable cutter and means for moving said cutter into cutting position including a 25 lever movable in a slot in the casing, means for varying the effective length of the slot comprising a collar rotatably mounted on the casing having a recess designed to register with said slot to a varying degree upon rotation of the collar, 30 the said collar having graduations thereon and an indicating pin on said casing co-operating with said graduations to gauge the degree of rotation of said collar and means for locking said collar in a given position.

35 8. A recessing cutter comprising a shaft, a cutter mounted on a shaft, a casing having an eccentric bore, means for projecting said cutter eccentrically of the casing including an eccentrically bored sleeve mounted in the bore of said 40 casing and carrying said shaft, and a lever connected to said sleeve, the casing having a slot through which said lever projects, said slot being of a length to provide for projection of the cutter to a maximum extent, and means for limiting the length of the slot for gauging the degree of eccentric projection of the cutter.

45 9. In a recessing cutter including a casing carrying a rotatable cutter and means for moving said cutter into cutting position, means mounted on the casing for locating the cutter at a given point within a tube including a slideable sleeve, a pin mounted on said sleeve designed to project therethrough, and spring means urging the pin towards said casing, releasable means for 50 withholding the pin against the action of the spring, said casing having a plurality of spaced apart and aligned recesses, the said pin being projected and locked in said recesses when in 55 registry therewith, said sleeve being notched at one end, and means on the casing co-operating with the notch in said sleeve for locating the pin in registry with a given recess whereby said pin will be projected into said recess when released.
